ELECTRIC SWITCH

Alvin W. Krieger, Milwaukee, Wis., assignor to
Cutler-Hammer, Inc., Milwaukee, Wis., a corporation of Delaware

Application December 10, 1935, Serial No. 53,748

6 Claims. (Cl. 200—153)

This invention relates to improvements in electric switches.

The primary object is to provide simple, efficient and inexpensive switches for control of the circuits of low voltage electric appliances for automobiles and the like.

Another object is to provide a new and improved form of mounting means for the switch.

Another object is to improve the appearance and the mechanical and electrical characteristics of switches of the aforementioned character.

Another object is to effect a novel combination of elements to provide a switch and an indicating light therefor.

Another object is to provide for use of a minimum number of different parts in the production of switches having substantially different electrical control characteristics.

Another object is to provide a switch having a novel form of movable contactor and a novel form of actuator therefor.

Another object is to provide a simple form of switch the actuating element of which is movable from an intermediate "off" position to one of two alternate "on" positions.

Another object is to minimize the cost of construction and assembly of the switch parts and the expense of mounting the switch upon the dashboard of an automobile.

Other objects and advantages of the invention will hereinafter appear.

The accompanying drawings illustrate certain embodiments of the invention which will now be described,—it being understood that the invention is susceptible of embodiment in other forms within the scope of the appended claims.

In the drawings,

Figure 1 is a top plan view of a combined switch and indicating light as constructed in accordance with my invention,—the bracket for attachment thereof to the dashboard being omitted.

Fig. 2 is a sectional view on the line 2—2 of Fig. 3.

Fig. 3 is a sectional view on the irregular line 3—3 of Fig. 2.

Fig. 4 is an end elevation showing the portion of the switch which is normally exposed when in use.

Fig. 5 is a bottom plan view of the switch.

Fig. 6 is a sectional view on the irregular line 6—6 of Fig. 5,—the mounting bracket being shown in assembled relation to the switch and in clamping position with respect to the inwardly extending flange of an automobile dashboard or the like.

Fig. 7 is a sectional view, on the line 7—7 of Fig. 11, showing a modified form of switch which may be used for speed control of the fan-driving motor of an automobile heater or the like.

Fig. 8 is a bottom plan view of the switch shown in Fig. 7.

Fig. 9 is a fragmentary sectional view on the irregular line 9—9 of Fig. 7 showing the actuating means for the double-contactor element of the switch,—the actuating means being shown in its intermediate position wherein both circuits or branch circuits are interrupted.

Fig. 10 is an end elevation of the switch of Figs. 7 to 9 showing the indicating means for operating with the actuating lever of the switch.

Fig. 11 is a sectional view on the line 11—11 of Fig. 10,—the mounting bracket being shown in assembled relation to the switch and to the dashboard of an automobile, and

Fig. 12 is a fragmentary sectional view similar to Fig. 9, but showing a slightly modified form of insulating member associated with the actuating lever of the switch,—the switch being shown in one of its on positions.

Referring first to Figs. 1 to 6, wherein I have shown a simple form of on and off switch which may be used for controlling energization and de-energization of the resistance element (not shown) of a "defroster" associated with the windshield of an automobile, the numeral 15 designates the metal casing which is drawn or stamped to the form illustrated in the several figures. Said casing is provided with four sides arranged substantially in the form of a rectangle,—with the exception that the front side 15^a is bowed outwardly or of arcuate form in cross section. The side 15^a may be provided with symmetrically arranged groups of beads or ribs 15^b and a formation such as shown at 15^c to provide a pleasing and attractive appearance to this portion of the device which is exposed when in use. The side 15^a of the casing is further provided with a symmetrically arranged window or opening 15^d through which light may be emitted upon energization of the signal lamp, as hereinafter described.

Casing 15 is partially closed at the upper end thereof by a wall portion 15^e and integral inwardly extending lugs or flange portions 15^f and 15^g. The opposite side walls 15^h and 15ⁱ of the casing are respectively provided with pairs of lugs 15^j, 15^k and 15^l, 15^m which are formed by shearing and pressing inwardly the material of the walls, as best illustrated at 15^j, 15^k in Fig. 6. The straight cut upper edges of said lugs are definitely

spaced from the plane of the upper end wall portion 15^e and lugs 15^f, 15^g to provide for reception with a sliding fit of one arm 16^a of a U-shaped metal bracket 16,—it being noted (Fig. 5

6) that the rear end wall 15^h of the casing is made relatively shorter than the other walls of the casing to accommodate the arm 16^a of said bracket.

The connecting portion 16^b of the bracket may 10 be made sufficiently long to accommodate the inner flange 17^a of the automobile dashboard 17, whether said inner flange is of the height illustrated or of any greater height common in the industry. The upper arm 16^c of the bracket is 15 provided with a threaded opening to receive the clamping bolt 18, the upper end 18^a of which is flattened and enlarged to facilitate manual tightening thereof, and the lower end 18^b of which is 20 preferably pointed to bite into the inner surface of the horizontal flange 17^b of the dashboard.

Each of the casing walls 15^h, 15ⁱ and 15^j is 25 provided with a sheared and inwardly pressed lug, two of which are shown at 15^e and 15^f in Fig. 6,—the lug (not shown) on wall 15^j being preferably vertically aligned with the aforementioned lug 15^m (Fig. 2). The cut edges of the last mentioned lugs are preferably spaced from the lower edges of the respective walls a distance equal to the thickness of a flat punched plate 19 of insulating 30 material which serves as the insulating base of the switch. Accordingly the base 19 is adapted to seat against the three lugs last mentioned, and the casing walls are provided with five integral lugs 15^a, 15^r, 15^s, 15^t and 15^u arranged in the manner best illustrated in Fig. 5,—said lugs being bent inwardly over base 19 to rigidly secure the same in position within casing 15.

Before inserting base 19 and bending inwardly the lugs 15^s and 15^t I prefer to insert a flexible 40 sheet 20 of transparent or translucent insulating material, such as Celluloid,—the form of said sheet being best illustrated in Figs. 3 and 6. As will be noted the major dimensions of sheet 20 are substantially equal to the dimensions of the 45 front end wall 15^a of the casing, and the arrangement is such that said sheet is interposed between said wall and the forward end of base 19 (see Fig. 6) to insure a curvature of the sheet corresponding to the curvature of said wall. 50 After bending of lugs 15^s, 15^t sheet 20 is restrained against outward displacement, as shown in Fig. 5. Sheet 20 is of a suitable color, preferably green, to remove the glare of the light when emitted through opening 15^d by the indicating lamp 55 hereinafter referred to.

The insulating base 19, which fits rather closely within the area defined by the four casing walls aforementioned, is provided on the inner surface thereof with a relatively long, flat stationary 60 contact 21 of substantially rectangular contour,—said contact being preferably formed of strip stock of the required width. Said contact 21 and base 19 are provided with aligned openings to accommodate a rivet 22, the hollow shank of 65 which penetrates an opening in a terminal plate 23 and is upset over the latter, as shown in Fig. 5. Terminal plate 23 is provided with a tapped opening to receive the shank of a binding screw 23^a, and base 19 and contact 21 are provided with 70 openings to afford clearance for said screw shank. The last mentioned opening in base 19 is provided with a relatively narrow or tapered extension, as shown at 24 in Figs. 1 and 2, to receive with a snug fit the relatively narrow downwardly angled lug 21^a formed integrally with contact 21,

whereby the possibility of rotary displacement of contact 21 with respect to rivet 22 is substantially eliminated.

The movable contactor 25 is preferably punched from a sheet of conducting material, such as phosphor-bronze, the resiliency of which is relatively high and remains high notwithstanding repeated bending thereof when in use. Superimposed upon the body portion of contact 25 is a substantially U-shaped clip 26 of resilient sheet metal,—the upper ends of the arms of said clip being bent outwardly, as indicated at 26^a, to facilitate insertion between said arms of the screw shell contact 27^a of an electric lamp 27 (Fig. 1). As will be apparent from consideration of Fig. 15, the casing 15 is grounded to the metal dashboard 17 by the aforescribed mechanical connection therebetween. Accordingly I prefer to shear a portion of the wall 15^h of the casing to provide an integral tongue 15^v which is offset inwardly as best illustrated in Figs. 1 and 2 to provide a resilient abutment for the center contact 27^v of the lamp. The wall 15^h of the casing is provided in its inner surface with a recess 15^w to receive the correspondingly shaped end of the bulb of lamp 27, whereby the lamp is securely restrained against accidental displacement.

The intermediate portion of clip 26 is provided with an opening registering with openings in contactor 25, base 19 and terminal plate 28, to 30 accommodate the rivet 29, the hollow shank of which is upset over said terminal plate, as shown in Fig. 6. Terminal plate 28 is provided with a binding screw 28^a the shank of which is accommodated by clearance openings provided in base 19 35 and contactor 25. As best shown in Fig. 2, the intermediate portion of clip 26 is provided with downwardly bent portions 26^v and 26^w which engage the side edges of contactor 25 to assist in preventing rotary displacement of said clip. 40

Contactor 25 is provided with an integral downwardly extending lug 25^a which engages the walls of the extension 30 of the opening in base 19 which provides clearance for the shank of screw 28^a whereby rotary displacement of contactor 25 45 with respect to base 19 is prevented. The forward end of contactor 25 is extended laterally as indicated at 25^b to overlap the forward end of contact 21,—the overlapping portion having a curved tip 25^c which is normally biased into engagement 50 with contact 21, as best illustrated in Fig. 3.

Base 19 is provided underneath the portion 25^b of the contactor with a substantially rectangular opening 31 (Figs. 3 and 6) which accommodates an insulating disk or roller 32 the diameter of 55 which is greater than the thickness of base 19. As aforesigned the contactor 25 is biased by the resiliency thereof into engagement with contact 21, as indicated in full lines in Fig. 3. When contactor 25 is so engaged it may be assumed that 60 a circuit is completed from a battery or other suitable source of electrical energy, through terminal plate 23, contact 21, contactor 25, terminal plate 28 to one terminal of the resistance of a windshield "defroster" or the like,—65 the other terminal of said resistance being connected to ground. In like manner a circuit may be traced in the manner aforescribed from the battery to contactor 25, thence through clip 26 70 and the screw shell terminal 27^a and filament of lamp 27, and through the center contact 27^v of the lamp and tongue 15^v to ground through the casing 15. Lamp 27 will therefore emit a beam of light through the aforementioned plate 75

20 and opening 15^d to indicate that the controlled circuit has been completed.

5 Interruption of the circuit through contact 21 and contactor 25 is effected by bodily displacing the disk or roller 32 upwardly to the dotted line position thereof indicated in Fig. 3,—whereby the tip 25^c of contactor 25 is moved to the dotted line position thereof out of engagement with contact 21. The means for effecting such movement 10 of roller 32 preferably comprises a punched sheet metal lever 33 having a circular or disk-like portion 33^a underlying the base 19 adjacent to the forward end of the latter. Portion 33^a is provided centrally thereof with an opening 33^b to pivot upon the relatively large diameter portion 34^a of a pin,—said portion 34^a being adapted to abut against the lower surface of base 19,—a portion 34^b of relatively smaller diameter being adapted to penetrate a correspondingly shaped 15 opening in base 19 and being upset over the latter as indicated at 34^c. Said pin is further provided with an enlarged head 34^d to retain said portion 33^a of the lever in assembled relation to base 19,—a bowed or convex annular 20 washer 35 being provided to resiliently retain the portion 33^a in bearing engagement with the lower surface of base 19.

The inner surface of portion 33^a is arcuately deformed, as best illustrated in Fig. 3, to provide 30 a track or groove having a depression 33^c of such depth as to accommodate the roller 32 in a substantially flush relation to the upper surface of base 19,—whereby engagement of tip 25^c of the contactor with contact 21 is permitted. 35 Upon movement of portion 33^a in a direction from left to right in Fig. 3 (which corresponds with movement of lever 33 in a direction from right to left in Fig. 2) the wall of said depression 33^c acts to lift roller 32, whereby disengagement of the contactor tip 25^c from contact 21 is effected (dotted lines Fig. 3). When roller 32 is thus raised it is permitted to seat within a slight depression 33^d, which affords a click or “feel” to indicate to the user that the switch is 40 in the off position. The resulting closure of the switch upon movement of lever 33 from the left-hand position (Fig. 2) to the right-hand position thereof shown in full lines will be apparent from the foregoing description.

50 I prefer to definitely limit the range of rotary movement of lever 33 whereby only an extreme on position and an extreme off position are provided. For this purpose I provide the inner surface of the portion 33^a of the lever with a stud 55 or projection 33^e which is preferably formed by an extruding operation, as best illustrated in Fig. 6. Base 19 is provided with a slot or opening 36 which is preferably of arcuate form as shown, and the stud 33^e is engageable with the 60 opposite end walls of opening 36 to positively limit the throw of lever 33 in opposite directions respectively. The handle portion 33^f of lever 33 is preferably of approximately triangular contour,—the portion 33^g of said lever being bent 65 or twisted so that handle 33^f is arranged in a plane at substantially right angles to the portion 33^a of the lever. Also as will be apparent from Fig. 2, the left-hand surface of the handle 33^f will serve as a reflector for the beam of light 70 emitted through the aforementioned opening 15^d to assist in indicating that the switch is in on position. As will be noted, the terminal plates 23 and 28, with their binding screws 23^a and 28^a, 75 are preferably of identical form, and the same

as shown are provided with wire beard guards or lugs 23^b and 28^b.

The construction of the switch illustrated in Figs. 7 to 12 is in certain respects quite similar to that aforescribed, and enables use of certain parts identical with those aforescribed and use of other parts formed from blanks identical with the blanks employed in constructing the switch of Figs. 1 to 6. To avoid confusion, however, I have used different reference numerals to designate the switch parts in Figs. 7 to 12.

Thus I employ a casing 37 having sides 38, 39, 40 and 41; the sides 38, 39 and 40 having lugs 38^a, 39^a and 40^a the cut edges of which form a 15 seat or abutment for the flat punched insulating plate 42 which forms the base of the switch. Lugs 38^b, 39^b, 40^b, 41^b and 41^c (Fig. 8) are adapted to be bent inwardly over plate 42 to retain the same in position within the casing. Casing 20 37 is provided with a top wall 43 which extends throughout a portion only of the area of the casing, and a pair of lugs are located in the plane of said top wall,—one of the pair of lugs being shown at 43^a in Fig. 11. The opposite 25 walls 38 and 40 are each provided with a pair of lugs the cut edges of which are spaced downwardly from the plane of top wall 43; the pair of lugs associated with wall 38 being shown at 38^c, 38^d in Fig. 11.

30 A bracket 44 like that aforescribed has the lower arm 44^a of the U slidably positioned between the top wall 43 and lugs (such as 43^a) and the cut edges of the lugs (such as 38^c, 38^d) associated with walls 38 and 40. The upper arm 35 of the bracket is provided with a threaded opening to receive the shank of the manually tightenable clamping screw 45, the pointed end 45^a of the shank of which bites into the upper surface of the flange portion 46^a of dashboard 46. 40

The front wall 41 of casing 37 may be embossed or otherwise formed as indicated at 41^e, 41^h and 41ⁱ to provide a pleasing and attractive appearance to the portion of the casing which is exposed at the front surface of the dashboard 45 46 (see Figs. 10 and 11). Said front wall 41 is also preferably provided with legends, such as shown at 41^d, 41^e and 41^f for cooperation with the handle portion 47^b of an operating lever 47 to indicate the low-speed, off and high-speed 50 positions of the switch mechanism. Base 42 is provided with a number of openings of suitable shape, arranged as shown in the several figures, to accommodate and to provide for attachment of the several switch parts. 55

The switch mechanism comprises a pair of stationary contacts 48 and 49, preferably formed of flat strip metal stock, and a contactor 50 which is punched and stamped from a sheet or strip of suitable resilient metal, such as phosphor 60 bronze. Contact 48 is secured flatwise to base 42 as by means of a rivet 51 which penetrates aligned openings in base 42 and terminal plate 52 and is upset over the latter (Fig. 8). Contact 48 is provided with an integral lug 48^a which 65 engages the walls of the reduced end 53 of an opening in plate 42 to prevent lateral displacement of said contact. The larger end portion (not shown) of opening 53 provides clearance for the shank of a binding screw 54 associated 70 with terminal plate 52, and contact 48 is likewise provided with an opening (Fig. 7) to afford clearance for said screw shank.

Contact 49 is rigidly attached flatwise to base 42 by a rivet 55, the hollow end of which is upset 75

over base 42 as shown in Fig. 8. Contact 49 is preferably provided with a lug 49^a which extends into a suitable opening in base 42 to insure against lateral displacement of said contact with respect to said base. The contactor 50 comprises a portion 50^a which is secured flatwise to base 42 as by means of a rivet 56 the shank of which penetrates an opening in terminal plate 57 and is upset over the latter (Fig. 8). Base 42 is provided with an opening 58 (Fig. 7) to afford clearance for the shank of binding screw 59 carried by plate 57. Contactor 50 is provided with a relatively narrow slit 50^b extending throughout the major portion of the length thereof whereby right-hand and left-hand contactor arms 50^c, 50^d are provided. Contactor 50 is likewise provided with a lug 50^e which engages the walls of an opening 60 in base 42 to assist in restraining said contactor against lateral displacement. The two arms 50^c and 50^d of contactor 50 are bent upwardly at a corresponding angle from the base portion 50^a, as best illustrated in Fig. 11, and said arms are then bent to extend downwardly toward the plane of contacts 49 and 58, respectively. The contactor arms 50^c and 50^d are respectively provided at their forward ends with lateral outward extensions 50^f, 50^g, and the tips 50^h, 50ⁱ of said extensions are bent downwardly whereby the same normally tend to engage the respective contacts 49 and 48. As will be noted, however, I provide the adjacent portions of extensions 50^f, 50^g with upwardly angled lugs 50^j, 50^k, of the character best illustrated in Fig. 9, and I interpose between the upper surface of base 42 and said extensions 50^f, 50^g an annular flat plate 61 of insulating material,—the thickness of plate 61 being such that in the intermediate position thereof illustrated in Fig. 9 the extensions 50^f, 50^g will be so spaced from the upper surface of base 42 as to insure disengagement of the contactor tips 50^h, 50ⁱ from the respective contacts 48 and 49.

The means for effecting movement of plate 61 toward each extreme position from the intermediate position thereof illustrated in Fig. 9 comprises an insulating stud or pin 62 the lower cylindrical end of which is seated, preferably with a fairly tight or drive fit, within a correspondingly shaped opening 47^c in the disk-like portion 47^a of the operating lever 47. Pin 62 is provided with an intermediate enlargement 62^a which is preferably of cylindrical form,—the lower end or shoulder formed by said enlargement 62^a being adapted to seat against the upper surface of the aforementioned portion 47^a of lever 47. The portion 62^b of pin 62 is positioned within the central opening in plate 61, and the rounded or hemispherical upper end of portion 62^b projects beyond the upper surface of plate 61. When the pin 62 is in the intermediate position thereof shown in Fig. 9 said rounded upper end thereof is located between the upwardly angled lugs 50^j, 50^k, and said lugs act to resist movement of the pin in either direction from said intermediate position, whereby a very definite "feel" of the lever in the off position of the switch mechanism is provided.

Base 42 is provided with an arcuate slot 63 (Figs. 8 and 9) which provides clearance for the enlarged portion 62^a of the pin. The means for limiting movement of pin 62 in opposite directions preferably comprises a stud or projection 47^d which is extruded from the upper surface of the portion 47^a of the operating lever,—base 42 having an arcuate slot 64 to provide clearance for stud 47^d and having end walls to be engaged

by said stud in each of the extreme on positions of the switch mechanism.

Referring more particularly to Fig. 9,—upon movement of pin 62 toward the left the rounded end of portion 62^b thereof cooperates with lug 50ⁱ in a cam-like manner to lift the tip 50^h of extension 50^f of the contactor arm 50^c still farther away from contact 49. At the same time pin 62 carries plate 61 toward the left out of engagement with the extension 50^g of the contactor arm 50^d, whereupon the inherent resiliency of said contactor arm results in downward movement of the tip 50ⁱ thereof into engagement with contact 48. Such a relationship of the parts is substantially illustrated in the modified form of switch shown in Fig. 12. In Fig. 12 a pin 65, having its lower end tightly fitted into the opening 47^c in portion 47^a of the operating lever, is provided with an enlargement 65^a having clearance in slot 63, and an integral annular extension 65^b, which corresponds with the plate 61 of Fig. 9. The rounded upper end 65^c of the extension in Fig. 12 corresponds in form and function to the rounded upper end of the portion 62^b of the pin in Fig. 9.

As will be apparent from Fig. 12, when the pin 65 is moved toward the right from the position thereof illustrated the peripheral edge of the annular extension 65^b will engage the angular lug 50^k with consequent lifting of the extension 50^g of contactor arm 50^d, whereby its tip 50ⁱ is disengaged from contact 48 to interrupt the circuit theretofore completed. At the same time the angular lug 50^j will act upon the rounded upper end 65^c of the pin extension to assist in bringing the pin to an intermediate position corresponding to that shown in Fig. 9,—the angular lug 50^k cooperating with said extension 65^b to resiliently resist movement of the pin farther toward the right, thus providing for the user of the switch an indication to the touch that the switch mechanism is in the intermediate or off position. In like manner, upon continued movement of pin 65 toward the right the rounded extension 65^c of the pin will act upon the angular lug 50^j to lift the extension 50^f of contactor arm 50^c whereby the tip 50^h of the latter is still farther separated from contact 48,—and at the same time the annular extension 65^b is disengaged from extension 50^f and its angular lug 50ⁱ to permit the tip 50ⁱ of the contactor arm 50^c to move by its own bias or resiliency into engagement with contact 49.

As best shown in Fig. 11 the operating lever 47 is pivotally supported with respect to base 42 as by means of a pivot pin the enlarged head 66 of which acts to retain the lever against substantial downward displacement relatively to the base. Said pin is provided with an intermediate portion 66^a against which the circular wall of the opening 47^e in portion 47^a of the lever is adapted to bear. Said pin is further provided with a reduced portion 66^b which penetrates a correspondingly shaped opening in base 42,—the hollow end of said portion 66^b being upset over the upper surface of said base, as shown at 66^c.

Referring now to Figs. 7, 8 and 10, let it be assumed that the terminal plate 57 (electrically connected with the contactor arms 50^c, 50^d) is connected to one terminal of a battery (not shown), the other terminal of the battery being connected to ground. It may also be assumed that the terminal plate 52 (electrically connected with contact 48) is connected to one terminal of a motor, such as that employed to drive the fan of an automobile heater,—the other ter-

5 minal of such motor being likewise connected to ground. Then upon movement of operating lever 47 to the right-hand dotted line position (Fig. 7) the tip 50^a of contactor arm 50^a is engaged with contact 48 to provide a direct connection between the aforementioned battery and the motor, with consequent operation of the latter at full or high speed (see Fig. 10).

10 However, if the operating lever 47 is moved to the left-hand dotted line position (Fig. 7) the tip 50^b of contactor arm 50^c is engaged with contact 49. A suitable length of resistance wire is interposed between the contacts 49 and 48,—said wire preferably being in the form of a helix 15 67 which is provided at opposite ends with straight portions 67^a, 67^b to support the same in spaced relation to the upper surface of base 42 (see Fig. 11); and said ends are provided with looped portions 67^c, 67^d which respectively 20 underlie the heads of rivets 55 and 51 to mechanically and electrically connect said helix to said contacts. Accordingly with lever 47 in the left-hand position thereof (Fig. 7) a circuit is completed from terminal plate 57 to contactor arm 50^c, through the tip 50^b of the latter to contact 49, thence through the resistance wire helix 67 to contact 48 and terminal plate 57. The motor controlled by the switch is therefore operated at low or reduced speed.

25 30 The primary purpose in forming the partial upper end wall 15^e and lugs 15^f, 15^g in the manner best illustrated in Fig. 1 is to facilitate insertion and removal of the electric lamp 27 after final assembly of the switch parts and prior to 35 insertion of the arm 16^a of bracket 16. When it is not desired to employ a signal lamp, the top wall 15^e might be formed to extend throughout substantially the entire area of the casing,—it being only necessary to insure that the rear 40 end wall 15^f of the casing is sufficiently short to provide for insertion of the bracket arm 16^a in the manner aforescribed. The particular form of the casing 15 shown in Figs. 1 to 6 is not only 45 desirable from the viewpoint of facilitating insertion and removal of the signal lamp, but it also enables production thereof by relatively simple punching and stamping operations. At the same time the amount or weight of the metal required in forming the casing is minimized. Accordingly the casing 37 employed in constructing 50 the switch of Figs. 7 to 12 is substantially identical with the casing 15 of Figs. 1 to 6, except for omission of the opening 15^d shown in Figs. 3, 4 and 6, and addition of the legends as shown at 55 41^a, 41^b and 41^c (Fig. 10).

55 In prior devices involving a switch and a bracket for mounting the same upon the lower flange of an automobile dashboard it has been customary to attach the switch to a projecting portion of the bracket by the usual one-hole mounting means. By employment of my improved construction (see Figs. 6 and 11) the mounting bracket is entirely concealed from view, and the switch projects only to the extent of its 65 own depth below the lower flange of the dashboard,—wherefore interference with leg room in the automobile is reduced to a minimum.

60 Due to the more complete styling of automobile dashboards it has become objectionable to 70 locate the switch within the area of the dashboard by the usual one-hole mounting arrangement. By my arrangement, however, the front end wall of the switch casing may have incorporated therein a design or shape which 75 forms to, or at least does not conflict with the

design or shape of the particular dashboard with which it is to be employed.

What I claim as new and desire to secure by Letters Patent is:

1. In an electric switch, in combination, a base 5 comprising a flat punched plate of insulating material, a pair of wiring terminal elements positioned upon the lower surface of said base, a contact and a contactor positioned upon the upper surface of said base and to which said wiring 10 terminal elements are respectively attached, said contactor being normally biased into engagement with said contact, a punched and stamped sheet metal operating lever pivotally supported upon the lower surface of said base and having a handle portion projecting beyond one end of the latter, said base having an opening formed therein and said lever having an integral lug engageable with the respective end walls of said opening to limit the oscillatory movements of said 15 lever, said base having another opening formed therein, an insulating member movable with respect to said last mentioned opening, said insulating member being adapted in one position thereof to permit movement of said contactor 20 under its bias into engagement with said contact, said insulating member when moved to another position thereof being adapted to move said contactor against its bias out of engagement with said contact, and said lever having an operative connection with said insulating member to provide for movement of the latter from each 25 position thereof to the other upon corresponding movements of said lever.

2. In an electric switch, in combination, an 30 insulating base, a pair of contacts positioned in spaced relation to each other upon the upper surface of said base, a contactor formed of resilient metal and positioned between said contacts, said contactor having a pair of forwardly extending 35 integral arms the forward ends of which are provided with lateral extensions to respectively overlie said contacts, said contactor being so formed as to normally provide for biasing of said extensions into engagement with said contacts, 40 an insulating member interposed between said base and the forward ends of said arms, said insulating member being adapted in an intermediate position thereof to engage both of said arms to withhold the extensions thereof from engagement 45 with the respective contacts, said member being movable in either direction from said intermediate position to selectively permit engagement of the respective extensions with said contacts under said bias, and means comprising an 50 operating lever pivotally supported by said base 55 for effecting such movements of said insulating member.

3. In an electric switch, in combination, a base 55 comprising a flat punched plate of insulation, a pair of punched sheet metal contacts seated flatwise in spaced relation to each other upon the upper surface of said base, a contactor formed of resilient sheet metal, said contactor having a rear end portion seated flatwise upon said upper 60 surface of the base, means for rigidly securing said contacts and the rear end portion of said contactor to said base, said contactor having a pair of integral arms extending forwardly between said pair of contacts, said arms having upwardly inclined lugs formed at the adjacent edges of the forward ends thereof, each of said forward ends having a lateral extension adapted to overlie one of said contacts respectively, the arms of 65 said contactor being bent to normally provide for 70 75

- engagement of the tips of said extensions with the respective contacts, an insulating member interposed between said base and the forward ends of said arms, said insulating member being adapted 5 in an intermediate position to engage both of said arms to withhold the tips of both of said extensions from engagement with the respective contacts, said member being movable in one direction to permit engagement of one of the 10 tips with its associated contact and in the opposite direction to permit engagement of the other tip with its associated contact, means associated with said insulating member and engageable by said upwardly inclined lugs to yieldably resist 15 movement of said member from said intermediate position and to afford a definite indication to the touch when said member is moved to said intermediate position, means comprising an operating lever pivotally supported upon the lower 20 surface of said base and projecting outwardly beyond one edge of the latter, said base and said lever having cooperating parts to definitely limit the throw of the latter, and said lever having a driving connection with said insulating member. 25 4. In an electric switch, in combination, an insulating base, a pair of wiring terminal elements positioned upon said base, a stationary contact and a non-rotatable, resilient contactor also positioned upon said base, means for electrically connecting said wiring terminal elements with said contact and said contactor respectively, said contactor being normally biased by its resiliency into engagement with said contact, an operating lever pivotally supported by said base and having a portion thereof projecting beyond one end of the base, said base and said lever having cooperating shoulders formed thereon to limit oscillatory movement of said lever, a pair of contacts associated with said base and adapted to receive 40 the center and shell contacts of an electric lamp, means providing an electrical connection between one of said pair of contacts and one of said terminal elements, the other of said pair of contacts being connected to ground, and said lever being operable to effect movement of said contactor toward and from the plane of said base into and out of engagement with said first mentioned contact to jointly complete and interrupt an internal circuit through the lamp contacts and an external circuit to an energy translating device of suitable form. 45 5. In an electric switch, in combination, an insulating base, a pair of wiring terminal ele- 50 ments positioned upon said base, a stationary contact rigidly attached to said base and electrically connected with one of said terminal elements, a resilient contactor having one end thereof rigidly attached to said base and electrically connected with the other terminal element, said contactor having a free end portion overlying one surface of said base and said stationary contact and normally biased into engagement with the latter, said base having an opening formed 55 therein in alignment with a portion of said contactor, an insulating member positioned within said opening, said insulating member being of greater height than the thickness of said base, a metal cam member supported for rotary movement relatively to said base at the surface of the latter opposite to said contactor, said cam member being adapted in one rotary position thereof to accommodate a portion of said insulating member whereby said contactor may move under its bias into engagement with said stationary contact, said cam member being also adapted upon rotary movement thereof from said position to effect movement of said insulating member and said contactor against the bias of the latter to effect disengagement thereof from said stationary contact, and manually operable means for effecting such rotary movement of said cam member relatively to said base. 6. In an electric switch, in combination, an insulating base, a stationary contact positioned upon the upper surface of said base, a contactor formed of resilient metal and attached to the upper surface of said base at one end of the latter, said contactor having an integral portion extending toward the opposite end of said base, the free end of said integral portion having a lateral extension which overlies a portion of said contact, said contactor being so formed as to normally provide for biasing of said extension into 40 engagement with said contact, an insulating member interposed between said base and said lateral extension, said insulating member being adapted in one position thereof to withhold said extension from engagement with said contact, 45 said insulating member being movable to another position thereof to permit engagement of said extension with said contact under said bias, and means comprising an operating member supported by said base for effecting movement of said insulating member from each position thereof to the other. 50

ALVIN W. KRIEGER.
